By His Attorneys,

UNITED STATES PATENT OFFICE.

FRANK H. SELLS, OF COLUMBUS, OHIO, ASSIGNOR OF ONE-HALF TO E. J. SWERER, OF SAME PLACE.

EMPLOYEE'S TIME-RECORDER.

SPECIFICATION forming part of Letters Patent No. 608,800, dated August 9, 1898.

Application filed January 6, 1898. Serial No. 665,832. (No model.)

To all whom it may concern:

Be it known that I, FRANK H. SELLS, a citizen of the United States, residing at Columbus, in the county of Franklin and State of 5 Ohio, have invented a new and useful Employee's Time-Recorder, of which the following is a specification.

My invention relates to employees' time-recorders, and has for its object to provide a 10 simple, compact, efficient, and durable construction and arrangement of parts capable of manipulation with facility to produce an accurate record of the times at which a plurality of employees report for and leave work, 15 the recording medium being so constructed as to adapt it to receive a record not only of the times at the beginning and end of a working day, but of the times at which the employees leave and return to work at the 20 noon or lunch hour.

A further object of the invention is to provide means for distinguishing between the records of reporting for and leaving work.

A further object of the invention is to provide a construction of inscribing mechanism whereby the record-sheet which is employed in connection with the recording mechanism may be made of the minimum simplicity to reduce the cost of a part which must be replaced after use, each record - sheet being adapted to receive the record for one working day, and hence being replaceable to provide a fresh sheet for each day.

A further object of the invention is to provide means for relieving the time-measuring mechanism of the resistance offered by the operation of the recorder and for relieving the operator of the necessity of imparting operative movement to the means whereby the inscribing medium produces the record upon the recording medium, whereby the uniformity of the record-marks is insured.

A further object of the invention is to provide means whereby the chronometer-controlled member of the mechanism is held in a fixed position during the production of a record.

Further objects and advantages of this invention will appear in the following description, and the novel features thereof will be

particularly pointed out in the appended claims.

In the drawings, Figure 1 is a front view of a recorder constructed in accordance with my invention. Fig. 2 is a side view of the 55 same with the contiguous side wall of the casing omitted. Fig. 3 is a front view with part of the front wall of the casing omitted. Fig. 4 is a detail horizontal section on the line 4 4 of Fig. 2 to show the escapement devices for controlling the advance movement of the recording medium. Fig. 5 is a detail horizontal section on the line 5 5 of Fig. 2 to show the clutch mechanism for holding the inscribing medium in a stationary position 65 during the recording operation and also to show the upper supporting devices for the record-cylinder. Fig. 6 is a horizontal section on the line 6 6 of Fig. 2 to show the lower supporting devices for the record-cylinder, 70 the means for imparting oscillatory movement to the same, and the feeding devices for the inking mechanism. Fig. 7 is a detail rear view of the means for varying the axial position of the record-cylinder. Fig. 8 is a 75 detail view in perspective of the clutch. Fig. 9 is a similar view of the supporting-arm for the type-wheel. Fig. 10 is a plan view of a portion of the record-sheet. Fig. 11 is a detail sectional view of the sliding connection 80 between the members of the record-cylinder spindle.

Similar numerals of reference indicate corresponding parts in all the figures of the drawings.

The apparatus embodying my invention is arranged within a suitable casing 1, and consists, essentially, of a recording medium having a record-cylinder 2, an inscribing medium having a type-wheel 3, and an inking medium having a ribbon 4 or its equivalent, said apparatus being controlled by a chronometer or time-measuring mechanism, such as a clock, (indicated in diagram at 5,) and having an exposed dial 6, traversed by hands similar 90 to those of an ordinary timepiece. The record-cylinder is preferably provided with a record or time sheet, a portion of which is indicated in plan in Fig. 10, and is divided transversely or circumferentially of the cylinder by lines 100

to form intervening spaces respectively designated by consecutively-arranged numerals to indicate hours. Said spaces are preferably grouped, with each group containing twelve spaces, numbered from "1" to "12," and referring, respectively, to the hours between twelve midnight and twelve m. The surface of the record or time sheet is also divided longitudinally or axially of the record-cylinder by parallel-spaced lines, forming spaces which are also numbered consecutively from "1" up, whereby the time-record of each employee may be arranged in a different space on the surface of the time-sheet, each employee having a number by which he is designated and in accordance with which he makes his record by means of the apparatus.

The record-cylinder is mounted for rotary movement, and with it is connected operating devices adapted for imparting a step-by-step advance movement in a uniform direction. The means shown in the drawings for accomplishing this object consist of a continuously-acting device, such as a cord 7, held under a constant tension and traversing a winding drum or spool 8, a weight 9 being shown as the means for maintaining said tension upon the cord, and the cord being arranged to traverse an intermediate direction-pulley 10, together with an escapement device adapted to release the spindle of the record-cylinder at intervals to permit its advancement under the tension of said operating device, the escapement in turn being controlled by a chronometer-controlled hour-wheel 11. This hour-wheel may be carried by an hour-shaft 12, consisting of an extension of the hour-hand arbor of the chronometer, and the wheel in the construction illustrated is provided with a trip-finger 13 for periodically engaging a trip-arm 14, carried by an escapement-lever 15, co-operating with an escapement-wheel 16, which is fixed to the spindle of the record-cylinder. The escapement-lever may be of the ordinary or well-known construction, yieldingly held in its normal position by means of an actuating-spring 17, and adapted to be moved from its normal position at intervals corresponding in time with the time designations on the record-sheet, or at intervals of one hour.

The record-cylinder is provided with a spindle of sectional construction, comprising a main member 18, capable of axial movement to correspondingly adapt the cylinder 2, which is fixed thereto, for axial movement, and a rotary member 19, to which are fixed the winding drum or spool 8 and the escapement-wheel 16. Inasmuch as in the construction illustrated the main member of the cylinder-spindle is mounted for axial movement, it is necessary to provide a sliding connection between the spindle members, and this I accomplish by providing the rotary spindle member 19 with a connected sleeve 20, having a longitudinal groove 21 for the reception of a lateral guide-stud 22 on the spindle member 18.

This provides for the communication of rotary motion from the spindle member 19 to the cylinder without interfering with the axial movement of the cylinder.

The inscribing medium in addition to the type-wheel 3 includes a spindle 23, parallel with the axis of the record-cylinder, upon which said type-wheel is mounted for axial movement, the hub 24 of said type-wheel being feathered upon the spindle to provide for the communication thereto of rotary motion imparted to the spindle, while permitting free axial adjustment of said wheel on the spindle. As above indicated, the surface of the recording medium is divided to indicate main intervals of time, as hours; but in order to adapt the apparatus for indicating time with sufficient definiteness for the purpose I have divided the circumference of the rotary member or wheel 3 of the inscribing medium to form spaces representing fractional intervals of time, such as minutes, and provided said intervals with type-faces for forming characters representing minutes. The type-faces or printing characters are adapted to be brought successively contiguous to or into operative relation with the surface of the recording medium, and hence I preferably employ means for imparting a continuous rotary motion to the spindle of the type-wheel. In the construction illustrated this operating mechanism consists of a winding drum or spool 25, traversed by a flexible connection 26, which is under a constant tension, and in practice I preferably form said connection 26 as an extension of the connection 7 and carry it through an eye 27 in the above-described weight 9, said extension or portion 26 of the connection traversing an intermediate direction-pulley 28. Obviously the rotation of the type or printing wheel spindle must be regulated to bring the printing characters into operative position or to the printing-point at intervals corresponding with the passage of time, and hence I employ a chronometer-governing mechanism similar to that employed for controlling the speed of rotation of the record-cylinder, and by connecting the spindle of the printing-wheel with the hour-shaft by means of intermeshing gears 12^a and 12^b I am enabled to use the same chronometer as that which is employed for driving said hour-shaft, and hence I am enabled to secure an accurate synchrony in operation between the inscribing and recording mediums. Thus by rotary adjustment of the printing-wheel of the inscribing medium I am enabled to bring different parts of its printing-face into operative relation with the recording-surface to indicate in the proper hour-spaces of the recording medium the number of minutes past a given hour at which the record is made, the movement of both recording and inscribing mediums being regulated by chronometer mechanism, as clearly set forth herein; but in order that the printing-wheel may be adjusted axially to arrange it in the hori-

zontal plane of either of the transverse series of spaces, and hence to enable each employee to make a record of his time independently of the records of the other employees, I employ an indicator, consisting of a dial 29, provided with characters corresponding with those on the record-sheet, representing different employees, as from "1" upward, and an index 30, traversing said disk and adapted to be arranged to indicate either of the characters thereon, said index being operatively connected with the printing-wheel, whereby the rotary adjustment of the index is adapted to impart axial movement to said wheel. In the construction illustrated the spindle 31 of the index carries a pinion 32, meshing with a rack-bar 33, to which is attached a supporting-arm 34, and this supporting-arm has connection with the hub 24 of the printing-wheel by means of a bifurcation 35 in the arm engaging a circumferential slot 36 in the hub. In practice I prefer to provide the index with a holding-pawl 37 to engage a holding-rack 38 on the disk, thus adapting the index to remain fixed at any point of adjustment during the subsequent manipulation of the parts to form the record.

Obviously it is necessary to secure coöperation or impact between the inscribing and recording mediums in connection with suitable inking mechanism, and hence I have provided means for imparting transverse or diametrical movement to the recording medium to bring it toward the periphery of the printing-wheel, the inking-ribbon 4 being interposed between the same to cause the inscribing of a character upon the surface of the recording medium. With this object in view I employ a swinging frame or support for the cylinder, the same consisting of a spindle 40, having upper and lower radial arms 41 and 42 for supporting the upper and lower ends of the main spindle member 18, the spindle 40 being mounted at its upper end in a bearing in the supporting-arm 43 and at its lower end in a socket-bearing 44. The upper arm 41 of the cylinder support or carrier engages the sleeve 20, and in order to adapt this sleeve for transverse movement I employ a flexible connection 45 between the sleeve and the spindle member 19, said connection consisting of a coiled spring, which is adapted to communicate rotary motion from the said spindle member 19 to the sleeve 20, and hence to the main spindle member 18, without interfering with the necessary transverse movement of the cylinder to bring it into operative relation with the printing-wheel of the inscribing medium.

The means illustrated in the drawings for accomplishing this printing movement of the record-cylinder consists of an operating-lever 46, of bell-crank construction, connected by a draw-rod 47 or its equivalent with a clutch 48, said operating-lever having an exposed push-button or finger-hold 49 arranged out-

side of the casing. The clutch consists of a swinging arm 50, carrying a beveled pawl 51 to engage a clutch-arm 52 on the spindle 40 of the cylinder support or carrier, said pawl having an actuating-spring 53, whereby it is yieldingly held in its normal position both in its swinging path of movement and also with relation to the arm 50. When the operating-lever 46 is actuated, the swinging arm 50 is drawn forward by the contact of the pawl 51 with the clutch-arm 52, and swinging movement is imparted to the cylinder support or carrier, and this movement continues until the extremity of the pawl 51 slips from the clutch-arm. The movement of the cylinder support or carrier by means of the operating-lever 46 is accomplished in opposition to the yielding resistance offered by an impact-spring 54, and hence when the clutch-arm 52 is released from the pawl 51 said cylinder support or carrier is promptly returned to its normal position and is driven forcibly into operative contact with the printing-wheel. When the push-button 49 is released after accomplishing the printing operation, the pawl is drawn back to its normal position and is allowed to pass beyond the clutch-arm 52 to occupy a position in rear thereof by the pivotal movement of the pawl. Thus a series of operations of the mechanism may be accomplished in rapid succession. In order to relieve the jar at the limit of the transverse movement of the cylinder and also to remove the surface of the cylinder from contact with the inking-ribbon, I employ a cushion 55, arranged in the path, preferably of the lower arm 42, of the cylinder support or carrier, the yielding quality of said cushion allowing the movement of the cylinder, after the contact of the arm 42 with the cushion, to bring the cylinder into proper contact with the ribbon and the latter into contact with the printing character on the wheel 3, but the resilience of said cushion being sufficient to immediately withdraw the cylinder from contact with the ribbon, and thus permit the succeeding rotation of the cylinder without allowing its surface to be marred by the ribbon. A cushion of rubber may be employed. Thus the operating devices which are employed for causing the printing movement of the operating parts of the mechanism are not depended upon to cause the movement of the cylinder toward the printing-wheel, but merely to draw the cylinder back from its normal position in opposition to the tension of the actuating-spring preparatory to the release of the cylinder and its automatic movement toward the printing-wheel. The result of this relative arrangement of parts is that the sharpness or intensity of the impact is controlled mechanically and does not depend upon the judgment of the operator. The cylinder must be moved back to a certain predetermined point before it will be released from the operating devices, and when

thus released its forward or operative movement is due to the operation of means having a constant tension.

- It is desirable in connection with the above-described mechanism to employ means for successively presenting fresh surfaces of the inking-ribbon at the printing-point, and hence I terminally connect the ribbon with ribbon-spools 56 and 57, a friction-brake 58 being arranged to coöperate with the spool 56 and feeding mechanism operatively connected with the operating-lever 46 being employed for advancing the spool 57. In the construction illustrated a feed-lever 59 is engaged with a slot 60 in the draw-rod 47 and is provided with a feed-pawl 61 for engaging a ratchet-disk 62 on the spool-spindle. A holding-pawl 63 is also employed in this connection to prevent backward rotation of the spool.
- As hereinbefore indicated, I have found it desirable to provide means for distinguishing between the records made by employees in reporting for and leaving work, and in order to accomplish this I have adapted the record-cylinder for axial movement by forming a sliding connection between the spindle members 18 and 19, such axial movement being designed to bring different portions of the surface of a record-space on the record or time sheet into the plane of the printing-wheel, said record-spaces being preferably elongated axially of the cylinder to allow room for the necessary axial adjustment of the cylinder without removing a given space thereof wholly out of the plane of the printing-wheel. To accomplish this, I mount the socket-bearing 44 for axial movement to vary the vertical position of the spindle 40 of the cylinder support or carrier and dispose a cam 64 in operative relation with said socket-bearing, whereby the adjustment of the cam causes the required movement of the cylinder support or carrier. Operation of said cam is secured by suitable mechanism controlled by an index 65, exposed exteriorly of the casing in operative relation with a suitable scale marked "Entering" and "Leaving" or "In" and "Out," as indicated in the drawings. The connections illustrated consist of an arm 66 on the spindle 67 of said indicator 65, a rock-shaft 68, connected with the cam 64 and having an arm 69, and a connecting-rod 70 between the arms 66 and 69. When the index-arm 65 is arranged in one of its adjusted positions, the cam is turned to lower the cylinder support or carrier, whereas when said index is arranged in its other adjusted position the cam is arranged to elevate said support or carrier.
- Another important feature of the mechanism embodying my invention consists of means for holding the printing-wheel of the inscribing medium in a fixed position during the printing of a record to avoid blurring the record, and the means employed for accomplishing this purpose is a holding-wheel 71, fixed to the spindle 23 of the printing-wheel

and provided with a peripheral series of seats corresponding in number with the printing characters on said printing-wheel, in combination with a stop-pawl 72, adapted to be thrown into engagement with either of the seats of the holding-wheel and preferably connected with the operating-lever 46, by which the printing operation is accomplished. In the construction illustrated the stop-pawl is connected by a rod 73 with said operating-lever 46, whereby the depression of the push-button checks the rotary movement of the printing-wheel spindle before the cylinder support or carrier has been moved in opposition to the tension of its actuating-spring a sufficient distance to allow its release, said engagement of the stop-pawl with the holding-wheel being maintained until after the cylinder has advanced to produce the impression and has been removed by the coöperating cushion from contact with the inking-ribbon. Obviously this checking of the movement of the printing-wheel must be accomplished without interfering with the connection of said spindle with the chronometer-regulating devices, and hence I construct the printing-wheel spindle in sections, the section 23^a thereof being the means for carrying the spool 25 and the gear 12^a, while the section 23^b carries the printing-wheel and the stop-wheel 71, said sections of the spindle having an intermediate torsionally-yielding connection 74, consisting of a coiled spring or the equivalent thereof. Furthermore, it is desirable to employ an alarm mechanism designed for indicating when a record has been made to prevent one employee from registering for others, and hence to the sleeve 20 I attach a yielding tongue 75 of a bell-hammer, a gong 76 being arranged in the path of said hammer, whereby when the cylinder is released from the clutch mechanism 48 and reaches its printing position with relation to the inscribing medium the bell is sounded.

The dial 29, which, with the traversing index, constitutes a designating device, is provided with a number of stations corresponding with the number of spaces in each longitudinal series on the time-sheet, said stations being consecutively designated by suitable characters relating, respectively, by election, to different employees and corresponding with those on the time-sheet. The printing-wheel is operatively connected, as above described, with the movable member of this designating device for change of position longitudinally with relation to the time-sheet to secure correspondence between the positions of the index on the dial and the printing or inscribing member and time-sheet. The chronometer-controlled step-by-step transverse movement of the time-sheet cylinder or carrier, constituting the recording medium, brings different hour-columns of the recording medium into the printing-plane, and the manually-controlled printing movement of the time-sheet carrier causes the impression of the minute

character (on the contiguous point of the inscribing medium) in a space located in the present hour-column opposite the designated employee-designating character.

5 Various changes in the form, proportion, and the minor details of construction may be resorted to without departing from the spirit or sacrificing any of the advantages of this invention.

10 Having described my invention, what I claim is—

15 1. A time-recorder having a removable recording medium superficially divided to form spaces designated by characters representing divisions of time, an inscribing medium having impression-producing characters representing divisions of time of a different denomination, chronometer-controlled means for operating said inscribing and recording me- 20 diums, and actuating devices whereby the recording and inscribing mediums may be brought into operative relation to produce an impression upon the former, substantially as specified.

25 2. A time-recorder having a recording medium superficially divided to form spaces designated by characters representing divisions of time, chronometer-controlled means for imparting a step-by-step advance movement 30 to the recording medium, an inscribing medium provided with impression-producing characters representing divisions of time of a different denomination, chronometer-controlled means for imparting advance move- 35 ment to the inscribing medium, and actuating devices whereby the recording and inscribing mediums may be brought into operative relation, substantially as specified.

40 3. A time-recorder having a recording medium provided with an impression-receiving surface divided into spaces arranged in hour-columns, and provided with employee-designating characters, chronometer-controlled means for imparting a step-by-step advance movement to the recording medium, an inscribing medium provided with printing characters representing fractional divisions of time, chronometer-controlled means for imparting advance movement to the inscrib- 45 ing medium to bring its characters successively to the printing-point, and actuating devices for bringing the inscribing and recording mediums into operative relation, with the inscribing medium in the plane of the 50 selected employee-designating character, substantially as specified.

55 4. A time-recorder having a recording medium provided on its impression-receiving surface with longitudinal hour-columns di- 60 vided to form employee-designating spaces, chronometer-controlled means for imparting step-by-step movement to the recording medium in a direction transverse to the hour-columns, an inscribing medium having print- 65 ing characters representing minor divisions of time, chronometer-controlled means for bringing the different printing characters of

the inscribing medium successively to the printing-point, employee-designating means for adjusting the inscribing medium parallel 70 with the hour-columns of the recording medium, and actuating devices for bringing the recording and inscribing mediums into operative relation, substantially as specified.

5. A time-recorder having a recording me- 75 dium provided on its impression-receiving surface with longitudinal hour-columns di- vided to form employee-designating spaces, chronometer-controlled means for imparting step-by-step movement to the recording me- 80 dium in a direction transverse to the hour-columns, an inscribing medium having print- 85 ing characters representing minor divisions of time, chronometer-controlled means for bringing the different printing characters of the inscribing medium successively to the printing-point, employee-designating means for adjusting the inscribing medium parallel with the hour-columns of the recording me- 90 dium, adjusting devices for moving the recording medium in a direction parallel with its hour-columns, and actuating devices for bringing the recording and inscribing me- 95 diums into operative relation, substantially as specified.

6. A time-recorder having an inscribing me- 95 dium provided with impression-producing characters representing minor divisions of time, chronometer-controlled means for actuating the inscribing medium, a record-cylinder 100 having superficial spaces representing major divisions of time and mounted for movement toward and from the inscribing medium, actuating devices for moving the record-cylinder into operative relation with the inscribing medium, chronometer-controlled means for imparting advance movement to the record-cylinder to bring different portions of its surface successively into the printing-plane, and flexible connections be- 105 tween said chronometer-controlled means and the record-cylinder, substantially as specified.

7. A time-recorder having an inscribing me- 110 dium provided with impression-producing characters representing minor divisions of time, chronometer-controlled means for actuating the inscribing medium, a record-cylinder 115 having superficial spaces representing major divisions of time and mounted for movement toward and from the inscribing medium, actuating devices for moving the record-cylinder into operative relation with the inscribing medium, chronometer-controlled means for imparting advance move- 120 ment to the record-cylinder to bring different portions of its surface successively into the printing-plane, and flexible connections be- 125 tween said chronometer-controlled means and the record-cylinder, said connections con- 130 sisting of a coiled spring, substantially as specified.

8. A time-recorder having an inscribing me- dium, provided with printing characters rep-

resenting minor divisions of time, chronometer-controlled actuating devices for bringing different printing characters of the inscribing medium to the printing-point, a record-cylinder adapted for movement toward and from the inscribing medium, a carrier upon which the record-cylinder is mounted, actuating devices for moving the carrier, and chronometer-controlled means for advancing the record-cylinder to bring different portions of its surface into the printing-plane, substantially as specified.

9. A time-recorder having an inscribing medium, provided with printing characters representing minor divisions of time, chronometer-controlled actuating devices for bringing different printing characters of the inscribing medium to the printing-point, a record-cylinder adapted for movement toward and from the inscribing medium, a swinging carrier upon which the record-cylinder is mounted, actuating devices connected with the carrier for moving the record-cylinder into operative relation with the inscribing medium, and chronometer-controlled means for advancing the record-cylinder to bring different portions of its surface into the printing-plane, substantially as specified.

10. A time-recorder having an inscribing medium, provided with printing characters representing minor divisions of time, chronometer-controlled actuating devices for bringing different printing characters of the inscribing medium to the printing-point, a record-cylinder adapted for movement toward and from the inscribing medium, resilient cushioning devices for normally maintaining the surface of the record-cylinder at an interval from the inscribing medium, actuating devices for bringing the record-cylinder into operative relation with the inscribing medium in opposition to said cushioning devices, and chronometer-controlled means for advancing the record-cylinder to bring different portions of its surface into the printing-plane, substantially as specified.

11. A time-recorder having an inscribing medium, provided with printing characters representing minor divisions of time, chronometer-controlled actuating devices for bringing different printing characters of the inscribing medium to the printing-point, a record-cylinder mounted for movement toward and from the inscribing medium, yielding means for normally maintaining the record-cylinder contiguous to its impression-receiving position and yieldingly resisting movement from said position, actuating devices for withdrawing the record-cylinder from its normal position in opposition to said yielding means, and chronometer-controlled means for advancing the record-cylinder to bring different portions of its surface into the printing-plane, substantially as specified.

12. A time-recorder having an inscribing medium, provided with printing characters representing minor divisions of time, chro-

nometer-controlled actuating devices for bringing different printing characters of the inscribing medium to the printing-point, a record-cylinder mounted for movement toward and from the inscribing medium, yielding means for normally maintaining the record-cylinder contiguous to its impression-receiving position and yieldingly resisting movement from said position, actuating devices for withdrawing the record-cylinder from its normal position in opposition to said yielding means, cushioning devices for yieldingly resisting the movement of the record-cylinder toward the inscribing medium, and for normally holding the same out of its printing position, and chronometer-controlled means for advancing the record-cylinder to bring different portions of its surface into the printing-plane, substantially as specified.

13. A time-recorder having an inscribing medium, provided with printing characters representing minor divisions of time, chronometer-controlled actuating devices for bringing different printing characters of the inscribing medium to the printing-point, a record-cylinder adapted for movement toward and from the inscribing medium, a spring-actuated carrier-frame for the record-cylinder, means for swinging the frame in opposition to its actuating-spring to withdraw the record-cylinder from the inscribing medium, and chronometer-controlled means for advancing the record-cylinder to bring different portions of its surface into the printing-plane, substantially as specified.

14. A time-recorder having an inscribing medium, provided with printing characters representing minor divisions of time, chronometer-controlled actuating devices for bringing different printing characters of the inscribing medium to the printing-point, a record-cylinder adapted for movement toward and from the inscribing medium, a spring-actuated carrier-frame for the record-cylinder, a releasing-clutch for swinging the carrier-frame in opposition to its actuating-spring to move the record-cylinder from the inscribing medium, operating means for actuating said clutch, and chronometer-controlled means for advancing the record-cylinder to bring different portions of its surface into the printing-plane, substantially as specified.

15. A time-recorder having an inscribing medium, provided with printing characters representing minor divisions of time, chronometer-controlled actuating devices for bringing different printing characters of the inscribing medium to the printing-point, a record-cylinder adapted for movement toward and from the inscribing medium, a spring-actuated carrier-frame for the record-cylinder, a releasing-clutch having a swinging arm and a clutch-pawl for engaging a clutch-arm on the carrier-frame, to swing the latter in opposition to its actuating-spring and move the record-cylinder from the inscribing medium, an operating-lever for actuating said clutch,

and chronometer-controlled means for advancing the record-cylinder to bring different portions of its surface into the printing-plane, substantially as specified.

5 16. A time-recorder having an inscribing medium, provided with printing characters representing minor divisions of time, chronometer-controlled actuating devices for bringing different printing characters of the inscribing medium to the printing-point, a record-cylinder mounted for movement toward and from the inscribing medium, manually-operated means for causing the movement of the record-cylinder to its printing position, a spindle operatively connected with the record-cylinder for imparting rotary motion thereto, operating devices at a constant tension for imparting rotary motion to said spindle, and chronometer-controlled trip mechanism for releasing the spindle at intervals, substantially as specified.

15 17. A time-recorder having an inscribing medium, provided with printing characters representing minor divisions of time, chronometer-controlled actuating devices for bringing different printing characters of the inscribing medium to the printing-point, a record-cylinder mounted for movement toward and from the inscribing medium, manually-operated means for causing the movement of the record-cylinder to its printing position, a spindle operatively connected with the record-cylinder for imparting rotary motion thereto, operating devices at a constant tension for imparting rotary motion to said spindle, and chronometer-controlled trip mechanism for releasing the spindle at intervals, the same including an escapement wheel and lever, and a trip-wheel arranged in operative relation with the escapement-lever, substantially as specified.

25 18. A time-recorder having an inscribing medium, provided with printing characters representing minor divisions of time, chronometer-controlled actuating devices for bringing different printing characters of the inscribing medium to the printing-point, a record-cylinder mounted for movement toward and from the inscribing medium, manually-operated means for causing the movement of the record-cylinder to its printing position, a spindle operatively connected with the record-cylinder for imparting rotary motion thereto, operating devices at a constant tension for imparting rotary motion to said spindle, an escapement device including an escapement wheel and lever, the lever being provided with a trip-arm, and a continuously-operated chronometer-controlled trip-wheel having a finger adapted for periodical engagement with said trip-arm, substantially as specified.

35 19. A time-recorder having an inscribing medium, provided with printing characters representing minor divisions of time, chronometer-controlled actuating devices for bringing different printing characters of the

inscribing medium to the printing-point, a record-cylinder mounted for movement toward and from the inscribing medium, manually-operated means for causing the movement of the record-cylinder to its printing position, a spindle operatively connected with the record-cylinder for imparting rotary motion thereto, a weight-cord under a constant tension connected with a spool on said spindle for imparting rotary motion thereto, and chronometer-controlled trip mechanism for releasing the spindle at intervals, substantially as specified.

70

75

80

20. A time-recorder having a record-cylinder mounted for axial and rotary movement, chronometer-controlled means for imparting rotary motion to the cylinder, cylinder-supporting devices mounted for movement parallel with the axis of the cylinder, an exposed index mounted for movement to occupy either of a plurality of stations, operating connections between said index and the cylinder-supporting devices for varying the axial position of the cylinder, an inscribing medium provided with printing characters, chronometer-controlled means for actuating the inscribing medium, and manually-controlled means for bringing the inscribing and recording mediums into operative relation, substantially as specified.

85

90

95

21. A time-recorder having a record-cylinder mounted for axial and rotary movement, chronometer-controlled means for imparting rotary motion to the cylinder, cylinder-supporting devices mounted for movement parallel with the axis of the cylinder, a cam arranged in operative relation with said cylinder-supporting devices, an exposed index mounted for movement to occupy either of a plurality of stations, operating connections between said index and the cam for varying the axial position of the cylinder, an inscribing medium provided with printing characters, chronometer-controlled means for actuating the inscribing medium, and manually-controlled means for bringing the inscribing and recording mediums into operative relation, substantially as specified.

105

110

115

22. A time-recorder having recording and inscribing mediums provided respectively with an impression-receiving surface and impression-producing type-faces, the former being designated by, and the latter forming, characters respectively representing divisions of time of different denominations, chronometer-controlled means for advancing the recording and inscribing mediums, an inking-ribbon interposed between the inscribing and recording mediums, and manually-controlled operating devices for moving said mediums into contact with the opposite surfaces of the inking-ribbon, substantially as specified.

125

23. A time-recorder having recording and inscribing mediums, provided respectively with an impression-receiving surface and impression-producing type-faces, the former being designated by, and the latter forming,

130

- characters respectively representing divisions of time of different denominations, chronometer-controlled means for advancing the recording and inscribing mediums, an inking-
5 ribbon interposed between the inscribing and recording mediums, movable supporting devices for the inking-ribbon, manually-controlled operating devices for bringing said mediums into contact with the opposite sur-
10 faces of the inking-ribbon, and operating connections between the ribbon-supporting devices and said actuating devices for the inscribing and recording mediums, substantially as specified.
- 15 24. A time-recorder having recording and inscribing mediums provided respectively with an impression-receiving surface having characters representing divisions of time, and impression-producing characters represent-
20 ing divisions of time of a different denomina-
tion, chronometer-controlled means for advanc-
ing the recording and inscribing me-
diums, an inking-ribbon interposed between the inscribing and recording mediums, man-
25 ually-controlled operating devices for bringing said mediums into contact with the oppo-
site surfaces of the inking-ribbon, and includ-
ing a reciprocable rod, adjustable carriers for the inking-ribbon, and ratchet mech-
30 anism for advancing the ribbon-carrying de-
vices and including a feeding-lever opera-
tively connected with said reciprocable rod, substantially as specified.
25. A time-recorder having a rotary record-
35 cylinder having characters representing divi-
sions of time, chronometer-controlled means for rotating said cylinder, a rotary inscribing medium having peripheral printing charac-
40 ters representing divisions of time of a differ-
ent denomination, and mounted for axial move-
ment parallel with the surface of the record-
cylinder, employee-designating devices opera-
45 tively connected with the inscribing me-
dium to impart axial movement thereto, chrono-
meter-controlled means for imparting ro-
tary motion to the inscribing medium, and
actuating devices for bringing the record-cyl-
50 inder into printing relation with the inscribing
medium, substantially as specified.
- 50 26. A time-recorder having a rotary record-
cylinder having characters representing divi-
sions of time, chronometer-controlled means for imparting rotary motion to the record-cyl-
55 inder, an inscribing medium peripherally pro-
vided with printing characters represent-
ing divisions of time of a different denomina-
tion, for impressing the surface of the record-cyl-
60 inder, and having a spindle upon which it is
mounted for axial movement parallel with the
surface of the record-cylinder, chronometer-
controlled means for imparting rotary motion
65 to the spindle of the inscribing medium, a
designating device having a movable member
operatively connected with the inscribing me-
dium for imparting axial movement thereto,
and actuating devices for bringing the record-
cylinder into operative relation with the in-
scribing medium, substantially as specified.
27. A time-recorder having a rotary record-
cylinder having characters representing divi-
sions of time, chronometer-controlled means
70 for imparting rotary motion to the record-cyl-
inder, an inscribing medium peripherally pro-
vided with printing characters represent-
ing divisions of time of a different denomina-
tion, 75 for impressing the surface of the record-cyl-
inder, and having a spindle upon which it is
mounted for axial movement parallel with
the surface of the record-cylinder, chronome-
ter-controlled means for imparting rotary mo-
80 tion to the spindle of the inscribing medium,
a supporting-arm for the inscribing medium
mounted for linear movement parallel with
the spindle of said inscribing medium, a des-
ignating device having a member operatively
85 connected with said supporting-arm, and ac-
tuating devices for moving the record-cyl-
inder into operative relation with the inscrib-
ing medium, substantially as specified.
28. A time-recorder having a rotary record-
cylinder having characters representing divi-
sions of time, chronometer-controlled means
90 for imparting rotary motion to the record-cyl-
inder, an inscribing medium peripherally pro-
vided with printing characters represent-
ing divisions of time of a different denomina-
tion, for impressing the surface of the record-cyl-
95 inder, and having a spindle upon which it is
mounted for axial movement parallel with the
surface of the record-cylinder, chronometer-
controlled means for imparting rotary motion
100 to the spindle of the inscribing medium,
chronometer - controlled actuating devices
yieldingly connected with the spindle of the
inscribing medium, actuating devices for
105 bringing the record-cylinder into operative
relation with the inscribing medium, and hold-
ing devices for locking the spindle of the in-
scribing medium in a fixed position during
110 the printing operation, substantially as speci-
fied.
29. A time-recorder having a rotary record-
cylinder having characters representing divi-
sions of time, chronometer-controlled means
115 for imparting rotary motion to the record-
cylinder, an inscribing medium peripherally pro-
vided with printing characters represent-
ing divisions of time of a different denomina-
tion, for impressing the surface of the record-cyl-
120 inder, and having a spindle upon which it is
mounted for axial movement parallel with the
surface of the record-cylinder, chronome-
ter-controlled means for imparting rotary mo-
125 tion to the spindle of the inscribing medium,
chronometer - controlled actuating devices
yieldingly connected with the spindle of the
inscribing medium, actuating devices for
130 bringing the record-cylinder into operative
relation with the inscribing medium, and hold-
ing devices operatively connected with
said record-cylinder-actuating devices, for
locking the spindle of the inscribing medium

in a fixed position during the printing operation, substantially as specified.

30. A time-recorder having a rotary record-cylinder having characters representing divisions of time, chronometer-controlled means for imparting rotary motion to the record-cylinder, an inscribing medium peripherally provided with printing characters representing divisions of time of a different denomination, for impressing the surface of the record-cylinder, and having a spindle upon which it is mounted for axial movement parallel with the surface of the record-cylinder, chronometer-controlled means for imparting rotary motion to the spindle of the inscribing medium, said chronometer - controlled means being flexibly connected with the spindle by means of a torsionally-yielding spring, a toothed holding-wheel carried by the spindle, a holding-pawl for engaging the teeth of said holding-wheel, and actuating devices operatively connected with the holding-pawl for bringing the record-cylinder into operative relation with the inscribing medium, substantially as specified.
- 25 31. A time-recorder having a rotary record-cylinder having characters representing divisions of time, chronometer-controlled means for imparting rotary motion to the record-cylinder, an inscribing medium peripherally provided with printing characters representing divisions of time of a different denomination, for impressing the surface of the record-

cylinder, and having a spindle upon which it is mounted for axial movement parallel with the surface of the record-cylinder, chronometer-controlled means for imparting rotary motion to the spindle of the inscribing medium, said chronometer - controlled means being flexibly connected with the spindle by means of a torsionally-yielding spring, a toothed holding-wheel carried by the spindle, a holding-pawl for engaging the teeth of said holding-wheel, and actuating devices operatively connected with the holding-pawl for bringing the record-cylinder into operative relation with the inscribing medium, substantially as specified.

35 32. A time-recorder having rotary recording and inscribing mediums, common means, consisting of a weight-cord, terminally reeled upon spools on the spindles respectively of said mediums, for imparting rotary motion thereto, chronometer-controlled governing devices for each of said spindles, and actuating devices for bringing the recording and inscribing mediums into operative relation, substantially as specified.

40 In testimony that I claim the foregoing as my own I have hereto affixed my signature in the presence of two witnesses.

45 FRANK H. SELLS.
